UNITED STATES PATENT OFFICE.

MATTHEW T. CHAPMAN, OF AURORA, ILLINOIS, ASSIGNOR TO THE AMERICAN WELL WORKS, OF AURORA, ILLINOIS, A CORPORATION OF ILLINOIS.

DEEP-WELL CENTRIFUGAL TURBINE-PUMP.

1,320,736.

Specification of Letters Patent.

Patented Nov. 4, 1919.

Original application filed January 8, 1918, Serial No. 210,583. Divided and this application filed February 1, 1919. Serial No. 274,526.

To all whom it may concern:

Be it known that I, MATTHEW T. CHAPMAN, a citizen of the United States, and a resident of Aurora, in the county of Kane and State of Illinois, have invented certain new and useful Improvements in Deep-Well Centrifugal Turbine-Pumps, of which the following is a specification, reference being had to the accompanying drawings.

10 This invention relates to that type of deep-well pumps wherein are employed suitably-incased centrifugal water-raising elements that are intended to be normally located below the level of the water in the well. In pumping apparatus of this character it is deemed of advantage to provide a plurality of discharge pipes connected at their lower ends with the casing that incloses the centrifugal pump members, through 15 which pipes the water is forced to and through a single outlet member at the surface. In the ordinary practice of installing apparatus of this general type it has been customary to send from the factory the various 20 pipe sections, and the parts designed to unite them, in a wholly unassembled condition,—the work of properly assembling and coupling them together being done at the well. Inasmuch as the labor available for such work is frequently unskilled and inexperienced in such matters it often follows 25 that the assembling is so poorly done as to render the apparatus as a whole unsatisfactory. When it is borne in mind that the rotary shaft for driving the pumps must be fixed and at all times maintained in an absolutely vertical position and that the lateral support relied upon to maintain such shaft in its vertical position is derived from 30 the discharge pipes, it will be very plain that the proper placing and securing together of the various sections that constitute each of the discharge pipes is exceedingly important. It is one of the objects of my 35 invention to provide improved means for connecting together in parallel relation a plurality of discharge-pipe sections to form units that can be transported to the place of use, such units being adapted to be secured together end to end, and the connecting devices that hold together the pipes of each unit being so arranged and constructed 40 that they properly receive and hold the sec-

tional casing in which rotates the pump-shaft and through which, also, lubricant is fed to various bearings, and thus insure the said shaft and its inclosing casing being readily and comparatively easily placed in the required vertical position by unskilled labor at the well, and insuring also the maintaining of such shaft and its casing during the operation of the pumping mechanism. By uniting the end portions of each set of pipes, and machining the ends of each discharge unit true and parallel, and also machining said openings through the pipe-uniting members, I am able to ship in assembled condition the various units that, when placed end to end, form the main portion of the discharge pipe system of a well and also form the lateral supporting means from which the pump-shaft and its casing are held vertical—which units are capable of being installed in a well properly and with comparative ease and rapidity, even by unskilled labor.

Further objects of the invention are to provide novel means for lubricating the lower bearing of the pump-shaft; to provide an effective water-seal above the pumps and within the casing that is located directly above the pumps, so as to prevent the pumps from drawing in air or losing their priming when the level of the water in the well falls below the pumps; to provide improved means for properly suspending the shaft and the runners attached thereto and also the inclosing casing that surrounds said shaft and supplies lubricant to the several bearings for the shaft; and to improve generally the construction and operation of pumping apparatus of this type,—all as illustrated in the drawings and more particularly described hereinafter. That which I believe to be new will be pointed out in the claims.

In the drawings:

Figures 1 and 2 are views partly in elevation and partly in vertical section of the upper and lower portions, respectively, of my improved apparatus, the pump-shaft and piping that connects the discharge-head at the upper end with the casing at the lower end with which the pumps communicate being broken away;

Fig. 3 is a central vertical section on the

line 3—3 of Fig. 1 through the discharge-head of the apparatus and parts connected therewith;

Fig. 4 is a horizontal section on the line 5 4—4 of Fig. 3, looking upward;

Fig. 5 is a detail, being a vertical section through one of the couplings for the shaft casing;

Fig. 6 is a plan view of the coupling shown 10 in Fig. 5;

Fig. 7 is a side elevation, partly broken away, of the pump discharge casing;

Fig. 8 is a vertical section taken at line 15 8—8 of Fig. 7;

Fig. 9 is a horizontal section at line 9—9 of Fig. 7;

Fig. 10 is a section at line 10—10 of Fig. 1, and showing a top view of the plate at the upper end of each discharge-pipe unit, 20 into which plate the pipe members are secured, and the central opening in which plate forms a portion of the bearing in which one of the shaft-casing couplings fits;

Fig. 11 is a top or plan view of the 25 flanges that are connected, respectively, to the lower ends of the pipes of each discharge-pipe unit, showing also the connecting plate that is bolted to said flanges, the said pipes being shown in section,—the view 30 being in effect a cross-section taken at line 11—11 of Fig. 1, but with the shaft and its casing omitted;

Figs. 12 and 13 are plan and edge views, 35 respectively, of the connecting plate shown in Fig. 11; and

Figs. 14 and 15 are views corresponding to Figs. 10 and 11, respectively, but with the parts shaped to adapt them for use with a three-pipe unit.

40 Referring to the several figures of the drawings,—

20 indicates water discharge pipes, each made up of a series of sections, and each line of pipe sections extending from the discharge-head at the top of the well to the casing that is located down in the well below the surface of the water being pumped, such pipes being connected to said discharge-head and casing as hereinafter described. The pipes are spaced a distance 45 apart and held by means of connecting devices at the upper and lower ends of the sections. Each two sections of pipe are connected together by means of a single plate 50 21 having openings therethrough near its opposite ends into which the said upper ends of the pipe sections are screwed. Upon the lower ends of each two pipe sections are 55 screwed flanges 22. As best shown in Fig. 60 11, each of these two flanges is provided with a lateral wing 23, and when the flanges are screwed upon the pipe sections they are to be so turned that the two wings 23 carried by the flanges, respectively, will be directed 65 toward each other. At this flanged

end, the pipe sections are rigidly connected together by a plate 24 resting upon the flanges 22 and wings 23 and bolted to said flanges. With two pipe sections thus connected together at their upper and lower ends, it is evident that the structure thus formed is a very rigid one as no independent movement of any of its parts is possible. In this rigid united condition the structure is then subjected to machining operations at 70 its end portions so as to make the end surfaces perfectly true and parallel with each other and the connecting devices comprising the single connecting plate 21. The winged flanges 22 and plate 24 are subjected to such 75 further machining operations as will insure a central passage therethrough and a sliding fit therein of a pump-shaft casing so that such casing shall when passed through such openings extend vertically and in parallelism with the said pipe sections. The central aligned openings for the passage of this shaft casing are of larger diameter than the shaft casing proper, whereby the enlarged central cylindrical portions of the couplings that 80 unite the sections of the shaft casing shall accurately and slidingly fit therein. After 85 being machined in the manner briefly referred to, each pair of pipe sections and the parts that rigidly connect their ends together are ready for shipment to the place of use, and when used in the construction of a pumping apparatus will be bolted to other similarly formed structures without having any of its parts disconnected or 90 changed from the condition in which it left the place of manufacture. These various pump units are very readily and comparatively easily connected together as there is no screwing together of the various pipe 95 sections, but all that is required to be done is to bolt the various units together. In so uniting them, they will be placed so that the under surfaces of the flanges 22 of one unit bear against the upper surface of the single 100 plate 21 of another unit and then the connecting bolts 25 are inserted through said flanges and plate, as therein indicated, and then the nuts on the bolts are to be tightened. In view of the machining of these abutting 105 surfaces in the manner described, it is evident that the ends of the units will properly fit one against the other so that the pipes 20 as a whole will extend from the top to the bottom of the well in almost perfect parallelism, and consequently insure perfectly aligned openings through the pipe connecting means, which insures also that the shaft and its inclosing casing will be inserted and maintained in place in parallelism with the 110 discharge pipes. The pump-shaft is indicated by 26; as is usual it is made up of sections secured together by couplings 27. 28 indicates the before mentioned inclosing 115 casing for the shaft 26, which is also made 120 of sections secured together by couplings 27. 28 indicates the before mentioned inclosing 125 casing for the shaft 26, which is also made 130

up, of course, in sections. These casing sections are connected together by a coupling 29, an enlarged view of which is shown in Fig. 5, from which it is seen that it comprises two screw-threaded end portions upon which the ends of the adjoining casing sections 28 are screwed and a cylindrical portion intermediate of the screw-threaded end portions, which intermediate portion is of materially larger diameter than the end portions. The casing sections are to be of such a length as to insure the enlarged cylindrical central portion of each coupling to lie within the opening formed through the abutting end connecting members of two of the said units, and as the central portion of the coupling has been machined to have a sliding fit within such opening, it is evident that the bearing thus formed between the parts insures the proper vertical position of the casing and its contained shaft. As shown in said Fig. 5, the upper and lower faces of the enlarged central portion of the coupling are each formed with an annular recess 30, the outer wall of which is inclined toward the axis of the coupling. The ends of the shaft casing screwed on to the coupling ends are to be so beveled as to approximately fit in such recesses 30, and thus making a more perfect union between said sections and the coupling. Each coupling is centrally and accurately bored to properly receive the pump-shaft 26 and form an extended bearing therefor. The shaft casing 28 also acts to conduct a suitable liquid lubricant from the top of the well to the various shaft bearings, and each bearing is, therefore, provided with one or more passages 31 therethrough for permitting such lubricant to pass down through the entire length of the casing. 32 indicates a pump-discharge casing having in its upper end suitable openings with which the lower ends of the pipes 20 of the lowermost unit communicates, such lowermost unit being connected to a flange 21^b of such casing by bolts passing through it and through the flanges 22 of such unit, as clearly shown in Fig. 2. 33 indicates a shaft bearing extending centrally of the casing 32 and preferably formed integral with radial supporting wings 34 that extend to the cylindrical wall of the casing. This bearing member 33 is lined with a brass sleeve 35 for forming the bearing proper at that point for the pump-shaft. To the shaft are to be secured any desired number of pump runners. In the construction illustrated, two runners are shown, indicated, respectively, by 36—37, the upper one 36 being located in the lower end of the casing and the other one being in a separate case 38 removably secured to the lower end of said casing 32. Between the abutting flanges of the parts 32 and 38 are inserted packing rings indicated by 39.

When the apparatus is first installed, I prefer to place a plurality of such packing rings at the joint, and from time to time some of such packing will be removed for the purpose of taking up the wear between the pump runners and that face of the casing against which the runner rotates. There may be any number of such cases 38, depending upon the number of runners employed, and the various cases will be secured together in the same manner that the casing 38 is shown as secured to the casing 32—that is by bolts extending through flanges on the respective parts with rubber packing rings interposed between them. To the lower end of the runner casing 38, shown in the drawings, is attached in a similar manner a cylindrical casing 40 open at its upper end so as to be in free communication with the lower runner casing 38, and having suitably attached to it at its lower end a suction pipe 41, through which water from the well is drawn into the pumping mechanism. This casing 40 suitably supports a bearing 42 for the lower end of the shaft 26, said bearing being as shown provided with a brass sleeve 43. At one side of the casing 40 is formed a lateral hollow extension or grease-cup 44, from the interior of which extends a passage communicating with the shaft bearing 42 that is held centrally in the said casing 40. In the chamber of this lateral extension 44 and in the said communicating passage that leads therefrom is placed a quantity of solid lubricant which is adapted to be fed forward so as to keep the bearing for the lower end of the shaft properly lubricated. The outer end of the member 44 is closed by a cap 45 screw-threaded into it, and between the inner end of such cap and the mass of solid lubricant is left a small space which is in communication with a short piece of pipe 46, said pipe also communicating at its upper end with the interior of the lower runner casing 38. The upper end of the short pipe 46 is suitably covered by a filtering material 47, preferably felt. With the pump in operation, water from the lower runner casting will be forced down through the pipe 46 against a loose plate or head that bears against the outer end of the solid lubricant, and thus forces such lubricant properly against the lower end of the shaft, and as the upper end of the pipe is protected by the filtering material, no foreign substance of any kind will be allowed to pass down and find its way to the shaft bearing. 48 indicates a cup-shaped cap upon the pump-shaft 26 directly over the bearing 42, said cap being secured to the shaft so as to rotate therewith, but being free to move up and down thereon. It can be so secured by a key and slot as usual in such connections. Above it and bearing against it is a coiled spring 49 suitably secured to the shaft so as

to rotate therewith. This spring pressed cap being always held in close contact with the upper end of the bearing 42 effectually prevents any sand or other foreign matter 5 that is carried by the water being pumped from entering and injuring such bearing.

Above the upper pump runner, the casing 32 is provided with a stuffing-box 50 containing two separate packings that surround 10 the shaft, the upper one of such packings being indicated by 51 and the lower one by 52. The upper end of the sleeve 50 is closed by a gland 53 screwed therein. The two packings are held properly compressed 15 around the shaft by two means, one of which is a coiled spring 54 located around the shaft and bearing at its upper end against the packing 51 and bearing at its lower end against the packing 52, the packings thus 20 being compressed, respectively, between said spring and the gland and between said spring and the lower end of the sleeve 50. The other manner in which such packings 25 are compressed is by means of the pressure of the water being pumped, said water being admitted to a vertical pipe 55 closed at its upper end and having openings in its wall surrounded by a screening material 56 as shown, such pipe communicating at its lower 30 end with a passage 57 that communicates with the space in which is located the spring 54. The outer end of this passage 57 is closed by a screw plug 57^a. Between the central bearing sleeve members 33 and 50 I provide 35 an integral enlargement, the side walls of which extend across the casing 32, with which walls they are integral. This construction provides a chamber 58 in which is held water or other lubricating liquid 40 to form a seal around the upper end of the packing box, the gland 53 of which projects into such chamber. At the ends of this chamber are formed openings 59 through the wall of the casing 32, the lower edge of 45 such openings being well above the top of the stuffing-box gland so that there will always be insured a sufficient quantity of water being retained in the chamber to form an effective water seal, and thereby preventing 50 the entrance of air around the pump rod that would pass down into the pump and prevent the proper working of the mechanism, when the water in the well is lowered unduly. During the normal operation of 55 the pump with the casing submerged, a free supply of water from the well to the chamber is insured by these openings 59. 60 indicates a collar secured by a set-screw or otherwise to the shaft 26. It is located in 60 the chamber 58 and serves as a baffle to the water that is forced through the packing 51 and to a large extent will prevent the admission of any water to the shaft bearing above the chamber.

65 61 indicates I-beams secured in position at

opposite sides of the well mouth, and upon which is suitably secured the plate 21 of the uppermost pipe unit. Against the machined upper face of this connecting plate 21 rests flanges 62 formed on the base of the discharge-head—such flanges being also formed true on their under surfaces to make a perfect fit with the plate 21. The plate 21 and flanges 62 of the discharge-head are bolted together as shown. The discharge pipes 70 communicate with and discharge into a Y-shaped connection 63 that in turn discharges into a large discharge pipe 64 bolted thereto. The discharge-head also comprises three legs 65, one of which is a short leg that rises from 75 near the upper end of the Y-shaped discharge member 63, and these legs at their upper ends support a platform 66. The shaft casing 28 at its upper end is screwed on to the lower end of a coupling 67, as best 80 shown in Fig. 3, which coupling passes through the said uppermost plate 21 and projects above the same, and such projecting portion is screw-threaded as shown, and upon such screw-threaded portion is a collar 85 68. This collar is provided with holes 69 in its edge into any one of which a suitable bar can be inserted for turning the collar on the screw-threaded coupling. By turning this nut as required, the coupling can, of 90 course, be drawn up and draw with it the shaft casing 28, thus exerting such a tension or pull on the casing sections 28 and their coupling members as to insure the casing as 95 a whole being properly held in a perfectly 100 vertical position. The collar 69 is held in its adjusted position by means of a lock-nut 105 70 screwed down against it. The pump-shaft is afforded a bearing by this coupling 67 just as in the case of the coupling members 29, and, as shown, the upper portion of the shaft projects up through the platform 66, and at its upper end has screw-threaded 110 upon it a coupling or head 71 which is held to the shaft by a key 72. This coupling or 115 head 71 rests upon the upper member 73 of a ball bearing device, the lower member being indicated by 74. Between these members 73 and 74 are interposed a series of anti-friction balls. The ball bearing device is located 120 within a cup-shaped receptacle 75, from the lower face of which extends downwardly a bearing sleeve 76 which is lined with suitable bearing material 77, preferably bronze, below which is a packing 77^a held in place by 125 a gland 78 screwed into the lower end of the bearing sleeve 76. The outer surface of the sleeve 76 is screw-threaded, and by means of nuts 79—80 located, respectively, above and below the platform 66 the cup-shaped 130 member 75 is securely held in place after the shaft has had the member 71 screwed and locked upon it. It will be understood that by a proper adjustment of these nuts 79—80, the shaft 26 can be adjusted whenever nec-

130

- essary to compensate for wear of the runners. When such adjustment is had, the screwing up of the lower nut, 80, tightly against the under face of the platform 66 5 will hold the cup-shaped member, 75 that supports the ball bearing devices securely in place, with the weight of the shaft borne by the upper nut 79. The cup-shaped member 75 is provided with an annular wall 81 10 that is concentric with the outer wall of such member, and by providing it there is formed an annular space 82 extending all around but separated from the ball bearing members that support the shaft. The inner portion 15 of the cup-shaped member 75, in which the ball bearing supporting members are located, is designed to be kept filled with oil, and as such lubricant and the ball bearings will heat when the pump is in operation, I 20 provide for a constant flow of cold water through the space 82 to counteract such heating tendency, and this I do by providing a supply pipe 83 which extends at its lower end into the Y-shaped discharge member 63 25 and at its upper end into the annular space 82. The lower end of this pipe 83 is shaped in any suitable manner to divert into the pipe some of the water passing through the discharge member. Such water so diverted 30 will circulate through the annular space 82 and will be discharged through another pipe 84 that is suitably connected to the cup-shaped member 75 near the bottom of said annular space 82 and passes down into the 35 discharge member 63, and has, as shown in Fig. 3, an end turned in the direction of the flowing stream. By this means the central portion of the cup-shaped member will be kept comparatively cool.
- 40 The shaft inclosing casing 28 is also utilized as a medium for conducting a lubricant in liquid form to the various shaft bearings. Such lubricant is inserted in the casing through a pipe 85 inserted in an opening 45 through the set nut 70, such pipe being in communication with a suitable lubricant receptacle, not shown. The lubricant upon being admitted will pass down through one or more passages 86 in the upper bearing 50 55 67, and thence down through the passage 31 in the various intermediate bearings 29, and will finally escape through a similar passage or passages in the bearing 33 to the chamber 58, escaping from there through the openings 59 into the well. The lubricant in its passage through the casing will carry with it the small quantities of foreign matter that would otherwise lodge around the bearings and injure them.
- 60 It is evident, of course, that in lieu of the two-pipe construction for each unit that has been described so far, a larger number of pipe sections to each unit might be employed, and in Figs. 14 and 15 I have illustrated a three-pipe structure. Referring to 65
- said figures, the three pipes there shown are indicated by 20^a and the single plate that connects such pipes together at one end and that corresponds to the single plate 21 is indicated by 21^a. The flanges at the other 70 end of the pipe sections, which correspond to the flanges 22 in the construction already described, are indicated by 22^a, their laterally extending wings by 23^a and the plate that lies over and is attached to the parts 22^a 75 and 23^a is indicated by 24^a. The other parts in said figures corresponding to the parts already described are indicated by the same reference numerals with the addition of the letter "a."
- 80 I do not herein claim broadly the construction and arrangement of parts comprising a plurality of pipe sections and the plates and flanges carried thereby for securing the several pipe members of a unit together, but only claim in this application such units when combined with the pump-shaft and its inclosing casing, as the construction of such pipe units separately considered forms the subject-matter of a pending application filed 90 by me on the 8th day of January, 1918, Serial No. 210,853, of which application the present application is a division.
- 85 The part 71 at the top of the apparatus shown is provided with a plurality of driving pins 87 which is one of the means used by which an electric motor may be connected for driving the shaft 26. Such electric motor may be mounted on the platform 66 or elsewhere as desired.
- 95 From the description of the construction and relative arrangement of parts, it is believed that the operation will be readily understood by those skilled in the art, and the advantages of the construction and arrangement of parts will be fully understood and appreciated.
- 100 What I claim as my invention and desire to secure by Letters Patent, is—
1. In a deep-well centrifugal pump, the 110 combination with a plurality of water-discharge units each comprising a plurality of pipes spaced a distance apart and connected at one end by a single plate into which they project and at their other end by flanges 115 screwed thereon and rigidly united by a plate, said two end plates having alined openings therethrough and having their outer faces parallel, of a sectional pump-shaft and a sectional casing surrounding 120 said shaft, the sections of said casing being connected by couplings that are positioned in and have a sliding fit within the alined openings in said connecting end plates, and pumping means connected to said shaft. 125
2. In a deep-well centrifugal pump, the 130 combination with a plurality of water-discharge units each comprising a plurality of pipes spaced a distance apart and connected at one end by a single plate into which they

project and at their other end by flanges 5
screwed thereon and rigidly united by a
plate, said two end plates having alined
openings therethrough and having their
outer faces parallel, of a sectional pump-
shaft and a sectional casing surrounding
said shaft, the sections of said casing being
connected by couplings each having a central
bore that forms a bearing for said shaft,
10 said couplings being positioned in and hav-
ing a sliding fit within the alined openings
in said connecting end plates, and pumping
means connected to said shaft.

3. In a deep-well centrifugal pump, the
15 combination with a plurality of water-dis-
charge units each comprising a plurality of
pipes spaced a distance apart and connected
at one end by a single plate into which they
project and at their other end by flanges
20 screwed thereon and rigidly united by a
plate, said two end plates having alined
openings therethrough and having their
outer faces parallel, of a sectional pump-
shaft and a sectional casing surrounding
25 said shaft, the sections of said casing being
connected by couplings having external
screw-threads upon which the casing sections
are screwed and having a machined
central portion located in and having a slid-
30 ing fit within the alined openings in said
end connecting plates, and pumping means
connected to said shaft.

4. In a deep-well centrifugal pump, the
35 combination with a plurality of water-dis-
charge units each comprising a plurality of
pipes spaced a distance apart and connected
at one end by a single plate into which they
project and at their other end by flanges
40 screwed thereon and rigidly united by a
plate, said two end plates having alined
openings therethrough and having their
outer faces parallel, of a sectional pump-
shaft and a sectional casing surrounding
45 said shaft, the sections of said casing being
connected by couplings having external
screw-threaded end portions upon which the
casing sections are screwed and having a
machined intermediate portion of larger
50 diameter than the screw-threaded end por-
tions, said enlarged intermediate portions
being located in and having a sliding fit
within the alined openings in said connect-
ing end plates and having grooves in their
55 upper and lower faces into which the ends
of the casing sections project.

5. In a deep-well centrifugal pump, the
combination with a plurality of water-dis-
charge units each comprising a plurality of
pipes spaced a distance apart and connected
60 at one end by a single plate into which they
project and at their other end by flanges
screwed thereon and rigidly united by a
plate, said two end plates having alined
openings therethrough and having their

outer faces parallel, of a sectional pump- 65
shaft and a sectional casing surrounding
said shaft, the sections of said casing having
beveled ends and being connected together
by couplings having external screw-threaded
end portions upon which the casing sections 70
are screwed, and having a machined inter-
mediate portion of larger diameter than the
screw-threaded end portions, said enlarged
intermediate portions being located in and
having a sliding fit within the alined open- 75
ings in said connecting end plates and having
wedge - shaped grooves in their upper and
lower faces into which the beveled ends of
the casing project when tightly screwed
upon the couplings. 80

6. The combination with a pump-shaft
and an inclosing sectional casing therefor,
the ends of the casing sections being inter-
nally screw-threaded, of a centrally-bored
coupling to receive and form a bearing for 85
the shaft, said coupling having externally-
threaded ends upon which the ends of the
casing sections are screwed and having an
enlarged intermediate portion in the upper
and lower faces of which are annular 90
grooves to receive the ends of the casing
sections when they are tightly screwed upon
the coupling.

7. The combination with a pump-shaft
and an inclosing sectional casing therefor, 95
the ends of the casing sections being beveled
and such end portions being internally
screw-threaded, of a centrally-bored cou-
pling to receive and form a bearing for the
shaft, said coupling having externally- 100
threaded ends upon which the ends of the
casing sections are screwed and having an
enlarged intermediate portion, in the upper
and lower faces of which are annular
grooves to receive the beveled ends of the 105
casing sections when they are tightly
screwed upon the coupling.

8. In a deep-well centrifugal pump, the
combination with a plurality of water-dis-
charge pipes arranged a distance apart and 110
means for connecting said pipes together,
of a pump-shaft, runners connected there-
with, a shaft-inclosing casing formed of
sections, couplings uniting said sections and
forming bearings for the shaft, said cou-
plings having a sliding fit in the means that 115
connect the pipes together and each having
a lubricant passage therethrough, a pump-
discharge casing with which the lower ends
of the said pipes communicate, a shaft bear-
ing in said pump-discharge casing also hav-
ing a lubricant passage therethrough, a 120
stuffing box in said last-named casing, and a
chamber intermediate of said stuffing box
and last-named bearing into which lubricant
passing down the shaft-casing and the said
passages in the bearings enters, said cham-
ber having communication with the well, 125

whereby a seal is maintained around the lower bearing in said pump-discharge casing.

9. In a deep-well centrifugal pump, the combination with a pump-shaft, runners secured thereto, and a bearing for the shaft, of a grease-cup, and means for diverting some of the water being pumped to a position in the cup to force said grease into the bearing.

10. In a deep-well pump, the combination with a pump-shaft, runners secured thereto, and a bearing for the shaft, of a grease-cup, means for diverting some of the water being pumped to a position in the cup to force said grease into the bearing, and means for filtering such water before it passes to the cup.

11. In a deep-well centrifugal pump, the combination with a pump-shaft, runners secured thereto, and a bearing for the shaft, of a grease-cup, a spring therein for forcing grease in the cup to the bearing, and a pipe for supplying water under pressure behind the grease in the cup, said pipe being connected to and having communication with the casing that incloses a portion of the pumping elements.

12. In a deep-well centrifugal pump, the combination with a pump-shaft, runners secured thereto, and a bearing for the shaft,

of a grease-cup, a pipe for supplying water under pressure behind the grease in the cup, said pipe being connected to and having communication with the casing that incloses 35 a portion of the pumping elements, and means for filtering the water that passes to the grease-cup before it passes through said pipe.

13. In a deep-well centrifugal pump, the combination with a pump-shaft, runners connected thereto, and a bearing for the shaft, of a grease-cup, means for forcing grease through the side wall of the bearing, 40 a cap slidingly but non-rotatably mounted 45 on said shaft, and means for holding said cap against the end of the bearing.

14. In a deep-well centrifugal pump, the combination with a pump-shaft and runners connected thereto, of a bearing for the shaft, 50 a cap slidingly but non-rotatably mounted on said shaft, and means for holding said cap against the bearing.

15. In a deep-well centrifugal pump, the combination of a shaft, runners connected 55 thereto, separate cylindrical casings for the runners, means for connecting such casings together, and packing rings adapted to be removed for taking up wear when the runners or cylindrical casings become worn.

MATTHEW T. CHAPMAN.
